UNITED STATES PATENT OFFICE.

WILLIAM A. STALEY, OF DES MOINES, IOWA, ASSIGNOR OF ONE-HALF TO ALBERT T. SCHRADER, JR., OF ST. LOUIS, MISSOURI.

CARRIER FOR ENVELOPS TO BE ADDRESSED.

1,288,252.

Specification of Letters Patent.

Patented Dec. 17, 1918.

Application filed January 26, 1918. Serial No. 214,037.

To all whom it may concern:

Be it known that I, WILLIAM A. STALEY, a citizen of the United States, residing at Des Moines, in the county of Polk and State of Iowa, have invented a new and useful Carrier for Envelops to be Addressed, of which the following is a specification.

The present invention relates to a holder or carrier for envelopes for feeding the same over a platen of a typewriter or other machine used for addressing the envelopes, and has for an object to provide a carrier which is adapted to maintain the envelopes in such position that they may be readily and consecutively advanced through the machine with the least possible movement of the platen.

Another object is to provide a strip for a carrier which is adapted to support a relatively large number of envelopes; which holds the envelopes from edgewise displacement in all directions; which admits the easy and quick positioning and removal of the envelopes upon and from the strip; and which is constructed to hold the envelopes in overlapping relation with the parts of the intermediate envelopes exposed which are to receive the address or other data.

The above, and various other objects and advantages of this invention will be in part described, and in part understood, from the following detailed description of the present preferred embodiment, the same being illustrated in the accompanying drawing,

55 wherein:

Figure 1 is an outer face view of a portion of a strip constructed according to the present invention, a number of envelopes of the usual type being mounted upon the strip.

40 Fig. 2 is a rear face view of the same, disclosing the projecting portions of the flap of the envelop and the upper corners of the same.

Fig. 3 is a perspective view of the same, 45 showing the front side of the strip and the overlapping envelopes carried thereby.

Fig. 4 is a view similar to Fig. 3 showing the rear side of the strip and the projecting portions of the envelopes.

50 Fig. 5 is a diagrammatic view illustrating a filled carrier strip applied to a platen.

Referring to this drawing the carrier comprises a strip 10 of suitable length for carrying the desired number of envelopes A. The

strip 10 is of a width slightly greater than that of the envelopes and is provided with a group of slits for each envelop. In each group there is formed a transverse relatively long slit 11 adapted to receive therethrough the free end portion of the flap B of the envelop, and a pair of spaced diagonal slits 12 arranged one near each lateral edge portion of the strip or carrier 10.

The carrier 10 may be formed from relatively tough paper or other suitable material capable of resisting tear in the handling of the strip, and which is of sufficient flexibility to pass freely over the platen and through the machine. The groups of slits 11 and 12 are arranged in closely spaced relation throughout the length of the carrier to support the envelopes in overlapping relation to an extent which uncovers only those portions of the envelopes which are adapted to receive the necessary data; thus accommodating a relatively large number of envelopes within the length of the carrier 10.

In the use of the carrier it is preferred to first apply an envelop to the lower end of the strip and to place the remaining envelopes successively thereon and upon each other in the overlapping relation above described. Each envelop is quickly attached to the carrier by first inserting the tip of the flap B through the adjacent slot 11 and then bending the upper corners of the envelop A sufficiently to engage them through the adjacent pair of diagonal slots 12, as shown at C.

The transverse slits 11 are of sufficient length to receive about two thirds of the flap B therethrough, the flap binding against the carrier at the ends of the slit 11 and working against the marginal portions of the slits 12 to hold the envelop from sliding longitudinally upon the carrier. As the slits 12 are formed diagonally or at substantially forty five degrees and extend in opposite directions, the edges of the slits 12 retain the envelopes from lateral displacement.

The envelop is thus securely held to the carrier with its lower portion free to receive the subjacent envelop therebeneath.

After the envelopes have been addressed, they may be readily removed from the carrier by grasping the lower free edges of the envelopes and drawing the latter down, buckling the flaps B sufficiently to disengage the upper corners C of the envelopes from

the diagonal slits 12, further downward movement of the envelope disengaging the flaps B from the slits 11.

When the carrier is loaded, it may be fed over a platen D, as shown in Fig. 5 with the envelope facing away from the platen to receive the desired imprints as the strip is advanced over the platen in the usual manner of sheets of paper.

10 It is of course understood that the carrier 10 may be of any suitable width adapted to accommodate long and short envelopes, and that the slits 11 and 12 may be arranged in any desired angular relation 15 with respect to each other to effect the result of retaining the envelope from longitudinal and lateral displacement, and in relatively close relation to minimize the required advancement of the platen for bringing the data receiving portions of the envelope into proper position to receive the imprints.

What is claimed is:

1. A carrier for envelopes to be addressed, comprising a flexible strip adapted to be fed over the platen of an addressing machine and provided with longitudinally spaced apart groups of slits arranged to receive the tips of the flaps and the upper corners of the envelopes to hold the same from longitudinal and edgewise displacement from the strip.

2. A carrier for envelopes to be addressed, comprising a strip adapted to be fed over a platen of an addressing machine, and provided with spaced opposed diagonal slits for engaging the upper corners of envelopes and with means to engage the flaps of the envelopes to maintain the envelopes on the strip.

3. A carrier for envelopes to be addressed, comprising a strip adapted to be fed over a platen of an addressing machine, and provided with spaced means for engaging the envelopes to maintain the same on the strip, said means being adapted to engage the up-

per edge portions of the envelopes for holding the envelopes from sliding upwardly upon the strip, and to engage the edges of the flaps of the envelopes for holding the latter from sliding downwardly on the strip.

4. A carrier for envelopes to be addressed, comprising a strip adapted to be fed over a platen of an addressing machine, and provided with spaced opposed means for engaging the envelopes at opposed edge portions to maintain the envelopes on the strip, the opposed means for each envelope being spaced from an adjacent opposed means a distance less than the height of the envelope to support the envelope in overlapping relation throughout the length of the strip with sufficient surface of the envelope exposed for receiving the addresses.

5. A carrier for envelopes to be addressed, comprising a strip adapted to be fed over a platen of an addressing machine, said strip having closely spaced apart groups of slits extending throughout the length of the strip, each group including a transverse slit adapted to receive the free end portion of the flap of an envelope and a pair of oppositely extending diagonal slits adapted to receive the upper corners of the envelope and being spaced from the transverse slit a distance for maintaining the upper corners and the end of the flap through their respective slits.

6. A carrier for envelopes to be addressed, comprising a strip adapted to be fed over a platen of an addressing machine and provided with spaced opposed means for engaging the upper edge portions of the envelopes to hold the envelopes from sliding upwardly on the strip, and provided with spaced transverse slits adapted to receive the free end portions of the flaps of envelopes for holding the latter against sliding downwardly on the strip.

WILLIAM A. STALEY.
